UNITED STATES PATENT OFFICE.

GEORGE THOMAS BUCKHAM, OF WESTMINSTER, LONDON, ENGLAND, ASSIGNOR TO
VICKERS LIMITED, OF WESTMINSTER, ENGLAND.

GUN-MOUNTING.

1,303,024.

Specification of Letters Patent.

Patented May 6, 1919.

Application filed July 20, 1917. Serial No. 181,928.

To all whom it may concern:

Be it known that I, GEORGE THOMAS BUCKHAM, a subject of the King of Great Britain, residing at Vickers House, Broadway, Westminster, in the county of London, England, have invented certain new and useful Improvements in or Relating to Gun-Mountings, of which the following is a specification.

10 This invention relates to gun mountings of the kind in which the carriage is displaceable vertically so that by moving the gun about its trunnions until it assumes a vertical or approximately vertical position, the carriage and the gun can be housed within a cavity or well closed by a suitable cover plate connected to the carriage.

20 According to the present invention the cover plate is so constructed as to close the cavity or well in a watertight manner when the carriage is lowered and is so connected to the carriage that when the latter is in its raised or firing position the said cover plate can be displaced to enable the gun to be 25 used for high angle fire.

30 In order that the said invention may be clearly understood and readily carried into effect, the same will be described more fully with reference to the accompanying drawings, in which:—

Figure 1 is a side elevation, partly in section, showing a constructional form of the invention with the gun carriage in its raised or firing position.

35 Fig. 2 is a view similar to Fig. 1, but showing the gun carriage in its lowered or housed position, and

Fig. 3 is a local section on an enlarged scale.

40 A is the gun and A' the carriage in which it is mounted. B is the cavity or well within which the gun and its carriage can be housed, and C is the aforesaid cover plate mounted on the carriage. A^x is the telescopic sight which when the gun is depressed assumes the position shown by Fig. 2. It is to be observed that when the carriage occupies its lowered or housed position, the gun is disposed entirely in the well, with its muzzle pointing downward.

45 Consequently, not only is the gun rendered entirely invisible, but the use of a protective muzzle cap is avoided, together with the necessity of carefully adjusting such cap before the carriage is lowered and of subse-

quently removing it after the carriage has been raised, the disposition of the gun in the well in the manner above indicated preventing water from entering the bore of the gun if, from any cause, it penetrates the 60 subsequently described joint between the cover plate and well.

In the example shown the cover plate C has arms which are pivoted at C' so as to enable the cover plate to be swung relatively to both the gun and the carriage from the position shown by full lines into the position shown by chain lines in Fig. 1; in the latter position of the cover plate the gun can be elevated through large angles for 70 firing at aircraft. The cover plate is locked to the carriage in either of its said positions, by a locking pin C² and suitable stops may be provided for limiting the movements of the cover plate which may have handles 75 for enabling it to be readily moved by hand. The cover plate is circular in plan and has on its underside a ring of suitable material for making a watertight joint with a flange B^x at the upper end of the cavity or well B 80 when the gun and its carriage are in the housed position shown by Fig. 2. The said cavity or well is constituted by a tube or trunk within which is disposed a rod b having a head b' that bears against the base of 85 the mounting and thereby supports the gun carriage. In contact with a shoulder on this rod is a plate or piston B' which is connected to a balance weight B². The rod b may be raised to lift the carriage to its firing position, by hydraulic power or otherwise.

90 Surrounding the base of the mounting is a ring D having two external flanges D', D² between which is a circumferential groove adapted to engage with the flange B^x at the 95 upper end of the well B. The upper flange D' comprises an interrupted collar d' adapted to pass through corresponding gaps in the flange B^x when the carriage is reaching its raised position. The ring D is then angularly displaced (for example by a tommy bar inserted through one or other of several bosses d, d' on the ring) into its locking position and the carriage is then supported by the flange B^x.

100 The ring D is provided with two internal flanges D³, D⁴ (see Fig. 3) of which the former bears against part of the carriage and the flange D⁴ against the base of the mounting. The said ring is made in two 110

parts which are bolted together after being placed in position.

What I claim and desire to secure by Letters Patent of the United States is:—

- 5 1. In a gun mounting, the combination with the gun carriage and a well in which said carriage and the gun are adapted to be lowered when the gun has been turned about its trunnions into an approximately vertical position, of a cover plate for closing the upper end of the well in a watertight manner when the carriage and gun have been lowered completely into the well, with the muzzle of the gun pointing downward, and
- 10 15 2. In a gun mounting, the combination with the gun carriage and a well in which said carriage and the gun are adapted to be lowered when the gun has been turned about its trunnions into an approximately vertical position, of a cover plate for closing the upper end of the well in a watertight manner when the carriage and gun have been lowered completely into the well, with the muzzle of the gun pointing downward, and

means for pivotally mounting said cover plate on the carriage so that the cover plate ³⁰ can be swung into a position to enable the gun to be used for high angle fire.

3. In a gun mounting, the combination with the gun carriage and a well in which said carriage and the gun are adapted to be lowered when the gun has been turned about its trunnions into an approximately vertical position, of a cover plate for closing the upper end of the well in a watertight manner when the carriage is lowered ⁴⁰ therein, an angularly displaceable member arranged on the mounting and having an interrupted collar, a member arranged contiguous to the top of the well and having gaps through which said collar can pass, ⁴⁵ said members being adapted to co-operate when the first mentioned member is angularly displaced, to retain the carriage in its raised or firing position.

In testimony whereof I affix my signature ⁵⁰ in the presence of two witnesses.

GEORGE THOMAS BUCKHAM
